UNITED STATES PATENT OFFICE.

RICHARD LICHTENBERGER, OF NEW HARMONY, INDIANA.

WIRE-SUPPORTING POLE.

1,162,294.

Specification of Letters Patent. Patented Nov. 30, 1915.

Application filed August 18, 1913. Serial No. 785,193.

To all whom it may concern:

Be it known that I, RICHARD LICHTENBERGER, a citizen of the United States, residing at New Harmony, in the county of Posey and State of Indiana, have invented 5 certain new and useful Improvements in Wire-Supporting Poles, of which the following is a specification.

This invention relates to poles for supporting wires, and more especially that class thereof which are generally used to carry cross trees provided with insulators to hold telephone and telegraph wires and the like, and it has for one of its objects the provision 15 of an improved pole of this character which is formed of a plurality of metallic members which are assembled into a predetermined length and may be varied as to such length or height in accordance with 20 such various requirements.

The invention has, furthermore, for its object the provision of a pole comprising a pair of standards which are connected laterally by means serving at the same time 25 as foot-holds for the linemen.

The invention has also for its object the provision of means (in connection with the means whereby the standards are maintained in spaced relation) whereby guy 30 wires may be attached thereto at such height as may be best suited for the purpose of avoiding trees or other obstacles frequently found in localities where the poles are placed.

35 Further objects of the invention will hereinafter appear and be particularly defined in the claim.

The invention has been clearly illustrated in the accompanying drawings in which 40 similar characters denote similar parts and in which:—

Figure 1 is a side view of a wire-supporting pole embodying my invention. Fig. 2 is a horizontal section on line 2—2 on an 45 enlarged scale. Fig. 3 is a horizontal section on line 3—3 of Fig. 1 also on an enlarged scale.

Referring to the drawings, 10, 11 denote a pair of standards preferably formed of 50 tubing or piping and having their lower ends seated within foot plates 12 which, in their turn, are supported on a bed of cement 13 forming the bottom of a ground-hole which is filled with another body of 55 cement 14 and thus maintains the parts in proper position. In the present instance I

have shown each of the standards 10 and 11 composed of a pair of lengths or sections, the upper sections 10' and 11' being attached to the lower sections by joints or 60 unions 15 and 16, respectively. At their upper ends these upper sections 10' and 11' are united by a cross-tie 17 in any suitable manner.

One or more cross-trees 18 are secured to 65 the standards, preferably by clips 19 which surround the outer face of the standards while their inner faces engage the side of the cross trees as will be readily understood.

The standards are maintained in spaced 70 relation by spacer members which may be of any suitable construction, but are shown herein as comprising upper ears 20 and lower ears 21 integral with vertical braces 75 22 which are connected by cross members 23 serving as foot supports for the linemen. The upper ears 20, (see Fig. 2) are formed by bending the lateral projections of the spacer member (which is preferably formed 80 of sheet metal of the form shown) so as to provide an extension 20' of double thickness adapted to receive an eye-bolt 25 to which a guy wire, illustrated at 26, Fig. 1, may be attached. The free end of the bent 85 lip 20 is preferably rigidly secured to the main body of the spacer member, as for instance by a rivet 27. In this manner the ear 20 really constitutes a tube which may be slipped onto the standard, while the lower 90 ear 21 has a plain bend or curl 28 (see Fig. 3) which is adapted to rest on top of the ear 20 of the next spacer member below.

The lowermost spacer member is firmly held against downward sliding movement 95 in any desired manner, and the upper spacer members may be either individually secured in like manner, or they may merely rest upon the lower member and upon each other.

By virtue of the construction embodying 100 the upper and lower ears connected by a cross-tie of considerable width, the entire structure will be stiffened against lateral swaying. Furthermore, inasmuch as these 105 spacer members are preferably formed of sheet metal they are very light in weight and yet strong, can be shipped in large quantities in compact form, and are inexpensive and of uniform standard size and shape, 110 and the necessity of boring or fitting the members on the uprights, by pins and holes

to be drilled thereinto is entirely obviated and avoids weakening of the parts.

The cross-trees may be equipped with any suitable supports for the wire insulators, 5 as may be deemed most expedient.

Changes may be made in the general organization, as well as in the particular construction of the combined spacer members and foot supports without departing from 10 the spirit of the invention, as well as in the manner of supporting the same on the standards.

I claim:—

In a supporting pole, a pair of standards, 15 spacer members connecting the standards and arranged one above the other with the lower end of each member resting upon the upper end of the next lower member, each of said spacer members being formed of

sheet metal and including vertical braces 20 connected by members, the ends of the vertical braces being extended laterally forming standard engaging sleeves, adapted to surround the standards for holding them in their vertical positions, fastening elements securing the sleeves and the standards, and the upper of the sleeves having their outer ends extended to produce ears of 25 double thickness joined at their outer edges and additional means connecting the said 20 ears.

In testimony whereof I affix my signature in presence of two witnesses.

RICHARD LICHTENBERGER.
